INVENTOR

S. H. Ransom

UNITED STATES PATENT OFFICE.

SAMUEL H. RANSOM, OF ALBANY, NEW YORK.

DESIGN FOR THE PLATES OF A PARLOR OR HEATING STOVE.

Specification forming part of Design No. 6,733, dated June 21, 1873; application filed April 18, 1873.

To all whom it may concern:

Be it known that I, S. H. RANSOM, of the city and county of Albany and State of New York, have invented a Design for the Plates of a Parlor or Heating Stove, of which the following is a specification:

The nature of my design is fully represented in the accompanying engraving, to which reference is made.

A represents the urn, formed as shown, and ornamented around the main or spherical part with a band of scale-work, and the several sections of the base with a series of leaves, the handles on each side being of fancy scroll-work. B represents the upper portion of the body, divided into several panels by strips and bands of scale-work, on the surface of which panels are the oval ornaments, composed of scrolls, leaves, and raised work, as shown. C represents the peculiarly-formed intermediate rim-plate, its upper surface being ornamented with a series of rosettes alternate with small spear-head formations, the lower portion being ornamented by graduated flutings and bead-work adapted to its peculiar crescent-shaped form. D represents the doors of the mica story, finished on their outer and inner edges with a series of bead-work and

finished at the top by rosettes. E represents an intermediate section, the upper portion of its surface ornamented with festoons, inverted, of bead-work, and its lower surface with festoons, of alternate shields and bead-work. F represents the base-section, ornamented with a series of festoons, inverted, of bead-work. From each end depend pearl-shaped pendants, alternate with fancy columns with scroll-work tops. G represents the main bottom of stove, ornamented with series of scalloped, beaded, raised work, alternate with fan-shaped and scrolled configurations on its upper or inner surface, and the small continuous "drop" work with bead-shaped finish around its lower or outer edge.

I do not claim the general formation of any of the moldings or other work except as mentioned in C.

What I claim as my invention is—

A design for the plates of a parlor or heating stove, substantially in the manner above mentioned.

S. H. RANSOM.
